UNITED STATES PATENT OFFICE.

FREDERICK C. MILLER, OF NEWPORT, KENTUCKY.

VARIABLE-SPEED MECHANISM.

SPECIFICATION forming part of Letters Patent No. 728,268, dated May 19, 1903.

Application filed July 14, 1902. Serial No. 115,526. (No model.)

To all whom it may concern:

Be it known that I, FREDERICK C. MILLER, a citizen of the United States, residing at Newport, in the county of Campbell and State of Kentucky, have invented certain new and useful Improvements in Variable-Speed Mechanism, of which the following is a specification.

My invention relates to a variable-speed device the principles of which apply to any machine organization in which a variety of speeds is a desideratum; but it is more particularly designed and arranged for application to automobiles.

The objects of the invention are to provide a simple construction which may be easily manipulated, in which the desired number of speeds, the reversing, and the connecting and disconnecting of the main drive may all be accomplished through the medium of a single controlling-lever.

The other features of my invention are more fully set forth in the description of the accompanying drawings, forming a part of this specification, in which—

Figure 1 is a central vertical section of my improvement. Fig. 2 is an end elevation of the shifting device. Fig. 3 is a section on line *x x*, Fig. 1. Fig. 4 is a section on line *y y*, Fig. 1, showing the controlling-lever. Fig. 5 is a section on line *z z*, Fig. 3. Fig. 6 is a detailed view of the actuating-cam.

A represents the casing, provided with driving-shaft *B* and driven shaft *C*. Shaft *B* is movable longitudinally of the casing.

P represents the driving-pulley. When shaft *B* is shifted in its bearings in the casing in the direction of driving-pulley *P*, the clutch is engaged and fixes the driving-pulley *P* to said shaft *B*, and likewise a reverse movement of shaft *B* uncouples the shaft from the driving-pulley.

1, 2, and 5 represent different-diameter gear-wheels fixed at intervals on shaft *B*.

4, 5, and 6 represent an opposing set of gear-wheels of different diameter on shaft *C*, the said gear-wheels being loose on shaft *C*, but adapted to turn therewith and to slide thereon independently.

As shown, the gear-wheels 4, 5, and 6 are provided with flanged hubs. Only three speeds, obtainable from the intermeshing of 1 and 4 or 2 and 5 or 3 and 6, are shown, al-

though the principle could be carried to any extent desirable or limited to two speeds without deviating from my invention. 55

Loosely journaled upon stud-shaft *B'*, to one side of driving-shaft *B*, is a reversing gear-wheel 7, always intermeshed with gear-wheel 5 on shaft *B*. Stud-shaft *B'* is long enough to permit of the sliding of gear-wheel 60 thereon, said gear-wheel being formed with an elongated face, which permits of its sliding on shaft *B'* while intermeshing with the teeth of gear-wheel 3.

Stud-shaft *B'* is supported in suitable bearings in the casing, the method of support and position of this shaft and its gear-wheel 7 being indicated in dotted and full lines, respectively, Fig. 1.

Each of the hubs of gear-wheels 4, 5, and 6 70 on shaft *C* and gear-wheel 7 on stud-shaft *B'* is provided with a groove.

a b c d represent arms provided with yokes *a' b' c' d'*, respectively, at their inner ends engaging into the grooved sleeves of gear-wheels 75 4, 5, 6, and 7.

e f g h represent shifting rods, the ends of which are loosely supported in the ends of the casing, permitting of the longitudinal movement of the rods relative thereto. These 80 rods *e f g h*, respectively, are connected to arms *a b c d*.

D represents a lever journaled concentrically with shaft *B* and movable rotatively transversely to the casing. To the upper end 85 of the lever *D* is pivoted a lever *E*, one end of lever *E* being provided with a handle, the other end of said lever *E* being connected to the end of shaft *B*. It is obvious that when lever *E* is rocked with shaft *B* as a center it 90 moves in unison with lever *D* and together they rock in the arc of a circle transverse to the casing, whereas when lever *E* is actuated on its center *E'* lever *E* moves independently in the longitudinal plane of the casing and 95 shifts shaft *B* endwise in its bearings to clutch and unclutch said shaft to driving-pulley *P*. The lower end of lever *D* is pivoted with a toothed segment *F*.

G represents a lever fulcrumed concentrically with shaft *C*. This lever has its upper half formed as a tooth-segment *H*, the teeth of which intermesh with the teeth of segment *F*, while the lower half of said lever

is formed with a peripheral camway I, having the abrupt crook or shoulder J. (See Fig. 6.)

The arrangement and intermeshing engagement of levers D G are shown in Fig. 4.

The ends of rods e, f, g, and h are provided with antifriction-rollers i, which ride in the camway I.

K represents the handle of lever E, which is projected opposite a ledge L, provided with notches m, (see Fig. 4,) the position of the lever relative to the respective notches denoting the speed obtainable at a given position or the reversing, as the case may be.

15 The direction of the length of the slot is transverse to the casing. The notches constitute locking-detents to hold the lever in adjusted position.

Mode of operation: The parts being in the position of Fig. 1—that is, shaft B unclutched and gear-wheel 5 being shifted to its predetermined position—the handle E is grasped and rocked in a direction along the length of the slot, as shown in Fig. 4. By this movement lever D turns on its center, and through the engagement of toothed segments F and H lever G is rocked on shaft C in the opposite direction from lever D. The semicircular cam-wheel I is thus partly rotated, which 30 movement successively presents the abrupt shoulder J to the antifriction-rollers i, respectively, on the ends of rods e, f, g, and h. This causes the rods to be shifted successively as the rollers ride in this cam, and hence successively shifts gears 4, 5, 6, and 7 on their respective shafts. A movement of lever E in either direction shifts the said gear-wheels successively back and forth on their shaft as the V-shaped cam J successively engages

40 the rollers of the shifting rods. As the said antifriction-rollers of the shifting rods ride in the main or straight channel-way of the cam, except when the shoulder J is brought into engagement therewith, they are only 45 actuated one at a time and as the rollers are respectively engaged by cam J. By the means so far described a selected gear-wheel is brought to a predetermined position—say, as shown in Fig. 1, gear-wheel 5 has 50 been shifted to the left on shaft C from its normal position shown in dotted lines. The position of the lever in its slot indicates that gear-wheel 5 is properly adjusted. The lever E is then rocked transversely to the 55 length of the slot and fitted into the opposite locking-notch, shifting shaft B to the right of the position shown in Fig. 1, which movement simultaneously intermeshes fixed gear-wheel 2 on shaft B with loose gear-wheel 5 in

60 adjusted position on shaft C and clutches shaft B to the driving-pulley P. Now say the reversing-gear is to be actuated, the handle of lever E is operated to unclutch shaft B, at the same time throwing out of mesh any 65 gears which may be in train between shafts B and C. Lever E is moved in the length of the slot until opposite the proper notch, which

indicates that the cam J has shifted rod h, and hence slid gear-wheel 7 to the left-hand end of its stud-shaft B', said gear-wheel still being in mesh with its driving gear-wheel 3. The shifting of gear-wheel 7 to the left brings it into mesh with gear-wheel 5 on shaft C, which is in its normal position at that time, the normal position being shown in dotted lines, Fig. 1, and the reversing-gears being shown in Figs. 3 and 5. Shaft B is then shifted into clutching position.

By the means herein shown and through the medium of a single operating-lever any 80 one of a series of variable-speed gears, as well as the reversing-gears, may be shifted into position while the power is off and only when the power is on.

The notches serve as locks as well as indicators. The movement of shifting the lever out of the notches into the channel of the slot unclutches shaft B. Thus it is obvious that the movable gears cannot be shifted on their shafts while the driving-shaft is clutched to 90 the driving-pulley.

I do not restrict myself to the particular relative arrangement of gear-wheels or organization shown, except wherein particularly claimed, as the principles of the invention 95 may be variously applied, and the relative arrangement of movable and fixed gears varied from the arrangement shown without material difference. Neither do I restrict myself to the particular cam-and-lever mechanism shown for actuating the movable gear-wheels, as various details other than I have shown can be worked out for this purpose by a skilled mechanic familiar with the principles of invention and particular arrangement 105 herein shown.

Having described my invention, I claim—

1. A variable-speed device consisting of a driving and a driven shaft, opposing sets of different-diameter gear-wheels on said shafts 110 respectively, the gear-wheels on one of said shafts being arranged to slide thereon and turn therewith, a lever mechanism having connection with the said sliding gear-wheels, adapted to independently slide said gear-wheels on their shafts, the shaft carrying the fixed gear-wheels being slidably longitudinally in its bearings, and means for shifting said shaft, whereby the sliding gear-wheels may be selectively and independently intermeshed with their opposing gear-wheels, substantially as described.

2. In a variable-speed device a driving and a driven shaft, a plurality of different-diameter gear-wheels fixed to one of said shafts, a corresponding set of different-diameter gear-wheels on the opposing shaft adapted to turn therewith and slide thereon, a shifting rod for each of the said sliding gear-wheels, a lever-and-cam mechanism having engagement with 130 all of said shifting rods, the shaft carrying the fixed gear-wheels being slidably longitudinally in its bearings, and means for shifting said shaft, whereby the said sliding gear-

wheels may be independently intermeshed with the opposing gear-wheels, substantially as described.

3. In a variable-speed device a driving and a driven shaft, a plurality of different-diameter gear-wheels fixed to one of said shafts and a corresponding set of different-diameter gear-wheels on the opposing shaft adapted to slide thereon and turn therewith, a shifting rod for each of the sliding gear-wheels, an arm connecting each of said rods to its respective gear-wheel, a cam engaging the ends of all the said rods, means for manipulating said cam, the shaft carrying the fixed gear-wheels being 15 slidable longitudinally in its bearings, and means for shifting said shaft, whereby the sliding gears may be moved on their shafts so as to be independently intermeshed with their respective opposing gear-wheels, substantially as described.

4. In a variable-speed device a driving and a driven shaft, a plurality of different-diameter gear-wheels fixed on one of said shafts, a plurality of different-diameter gear-wheels 25 mounted upon the opposing shaft and being adapted to slide thereon and turn therewith, one of said shafts being slidable longitudinally, a plurality of shifting rods each connected respectively to one of the sliding gears, 30 a cam-wheel engaging said rods, a rock-lever for actuating said cam-wheel, an operating-lever pivoted respectively on said rock-lever and to the sliding shaft, whereby the sliding gears may be independently controlled, and 35 whereby the sliding shaft may be independently operated by the manipulation of a single lever, substantially as described.

5. In a variable-speed device a driving and a driven shaft, an opposing set of different-diameter gear-wheels, some of said gear-wheels being fixed on said shafts and others being loose and adapted to slide on and turn with their shafts respectively, shifting rods each having connection with one of said sliding 45 gear-wheels, and a cam-and-lever mechanism common to all of said shifting rods, the shaft carrying the fixed gear-wheels being slidable longitudinally in its bearings, and means for shifting said shaft, whereby the said sliding 50 gears may be independently controlled, substantially as described.

6. In a variable-speed device a driving-shaft slidable longitudinally, a driven shaft, opposite sets of different-diameter gear-wheels on 55 said driven shaft, some of said gear-wheels being fixed and the others slidably mounted on said shafts, shifting rods, each being connected respectively to one of said sliding gear-wheels, a cam common to all of said rods and 60 adapted to reciprocate said rods, a rock-lever fulcrumed on the driving-shaft, adapted to actuate the said cam, and an operating-lever pivoted to the said rock-lever and to the said sliding shaft, whereby said sliding gears may 65 be independently controlled, substantially as described.

7. In a variable-speed device a driving and

a driven shaft therein, opposing sets of gear-wheels of different diameter, some of which are fixed to one of said shafts and some of 70 which are movable on the other of said shafts, one of said shafts being longitudinally movable, shifting devices independently connected to each of the movable gears, a cam engaged by each shifting rod, means for actuating said cam adapted to shift any one of 75 said movable gear-wheels into predetermined position, and means for sliding said movable shaft, whereby a fixed gear thereon is intermeshed with the particular movable gear on 80 the opposing shaft which has been shifted into predetermined position for engagement, substantially as described.

8. In a variable-speed device a driving and a driven shaft, an opposing set of different-diameter gear-wheels, some of which are fixed to and some of which are movable on their respective shafts, the shaft carrying the fixed gear-wheels being longitudinally movable in 85 its bearings, a power-wheel and a clutch between said movable shaft and power-wheel adapted to be engaged and disengaged by the shifting of said shaft, shifting rods independently connected to each of the movable gear-wheels, a cam independently engaged by each 90 shifting rod, means for actuating said cam adapted to shift any one of said movable gear-wheels into predetermined position on its shaft, and means for shifting said movable shaft whereby a fixed gear thereon is brought 95 into train with the particular movable gear on the opposing shaft which has been shifted into its predetermined position for engagement, substantially as described.

9. In a variable-speed device a driving and a driven shaft therein, an opposing set of different-diameter gear-wheels some of which are fixed to and others being movable on their respective shafts, a shifting rod and connecting-arm for each movable gear-wheel, a cam 105 rotatable in the arc of a circle transversely to the length of the shafts, each of said rods having engagement with said cam so as to be independently and successively shifted when said cam is rotated, means for rotating said 110 cam, the shaft carrying the fixed gear-wheels being slidable longitudinally in its bearings, a lever mechanism adapted to shift the said shaft, and also to actuate the said cam, whereby the movable gear-wheels may be selectively 115 and independently intermeshed with the opposing fixed gear-wheels, substantially as described.

10. In a variable-speed device a driving and a driven shaft, an opposing set of different-diameter gear-wheels, some of which are fixed to and some of which are movable on their respective shafts, a shifting rod and connecting-arm for each movable gear-wheel, a cam rotatable in the arc of a circle transversely to 125 the length of the shafts, each of said rods having engagement with said cam so as to be independently and successively shifted when said cam is rotated, an actuating-lever and

intermeshing toothed segments connecting said lever and cam, the shaft carrying the fixed gear-wheels being slideable longitudinally in its bearings, and means for shifting said shaft, substantially as described.

11. In a variable-speed device a driving and a driven shaft, an opposing set of different-diameter gear-wheels, some of which are fixed to and others of which are movable on their respective shafts, a cam concentrically fulcrumed relative to one of said shafts, provided with a toothed segment, each of said rods having engagement with said cam so as to be independently and successively shifted when said cam is rotated, an actuating-lever concentrically journaled relative to the other of said shafts, and having a toothed segment intermeshing with the toothed segment of said cam, substantially as described.

12. In a variable-speed device, a driving and a driven shaft, an opposing set of different-diameter gear-wheels, some of which are fixed to and others of which are movable on their respective shafts, the shaft carrying the fixed gear-wheels being slideable longitudinally in its bearings, and means for shifting said shaft, a cam rotatable in the arc of a circle transversely to the length of the shafts, a shifting and connecting arm for each movable gear-wheel having engagement with said cam, whereby said rod may be independently and successively shifted when said cam is rotated, a lever for rotating said cam, and an opposing ledge provided with indicating-notches, substantially as described.

13. In a variable-speed device a driving and a driven shaft, an opposing set of different-diameter gear-wheels, some of which are fixed to and some of which are movable on their respective shafts, one of said shafts being movable endwise in its bearings, a power-wheel, a clutch adapted to connect and disengage said movable shaft and power-wheel when said shaft is shifted, a shifting rod and connecting-arm for each movable gear-wheel, a cam rotatable in the arc of a circle transversely to the length of the shafts, said rods having engagement with said cam, whereby they are independently and successively shifted as the cam is rotated, a lever for rotating said cam, an actuating-lever pivoted to said first-named lever and to the movable shaft, whereby the shifting of said movable shafts and gear-wheels may be independently controlled through the medium of a single operating-lever, substantially as described.

14. In a variable-speed device a driving and a driven shaft, an opposing set of different diameter gear-wheels, some of which are fixed to and some of which are movable on their respective shafts, one of said shafts being movable endwise in its bearings, a power-wheel, a clutch adapted to connect and disengage said movable shaft and power-wheel when said shaft is shifted, a shifting rod and connecting-arm for each movable gear-wheel, a cam rotatable in the arc of a circle trans-

versely to the length of the shafts, said rods having engagement with said cam, whereby they are independently and successively shifted as the cam is rotated, a lever for rotating said cam, an actuating-lever pivoted to said first-named lever and to the movable shaft, whereby the shifting of said movable shafts and gear-wheels may be independently controlled through the medium of a single operating-lever, a notched ledge in the casing opposite which said operating-lever projects, the length of the ledge being transverse to the shafts, and the notches being transverse to the length of the ledge, whereby the movable gear-wheels can be shifted only when the movable shaft is unclutched, substantially as described.

15. In a machine of the class described, in combination with the movable gear-wheels, movable shaft and shifting rods connected to the movable gear-wheels, a cam common to all of said rods, said cam being provided with a toothed segment, and journaled concentrically to one of said shafts, a lever fulcrumed concentrically to the other of said shafts, and having a toothed-segment engagement with the segment of said cam, an actuating-lever connected to the movable shaft and pivoted to said first-named lever, a casing formed with a notched ledge, opposite which said lever projects, the length of the ledge being transverse to the length of the shafts, permitting the actuating-lever to be rocked in unison with the first-named lever in either direction of the length of the slot for shifting said gears on their shafts, and permitting the actuating-lever to be rocked independently of said first-named lever transversely to the length of the ledge and into and out of the locking-notches for shifting said movable shaft, substantially as described.

16. In a machine of the class described comprising a driving and a driven shaft, a driving and a driven gear-wheel on said shafts adapted to be intermeshed by sliding one of said gear-wheels on its shaft, a second gear-wheel on the driving-shaft, a stud-shaft, a pinion thereon always in mesh with said second driving gear-wheel, a shifting rod for each movable gear-wheel, and a common actuating cam and lever whereby one of the movable gear-wheels on the driven shaft may be intermeshed with either the driving-gear or the reversing-gear, substantially as described.

17. In a machine of the class described comprising a driving and a driven shaft, fixed and movable gear-wheels thereon, a stud-shaft, an elongated pinion thereon having constant engagement with one of the fixed gear-wheels on the driving-shaft, and adapted to be slid on its stud-shaft, shifting rods for each movable gear-wheel, a cam common to all of said shifting rods, and an actuating-lever for the cam, whereby the movable gear-wheels may be intermeshed with either the direct or the reversing gear-wheels, substantially as described.

18. In a variable-speed device, a shaft having a series of different-diameter gear-wheels fixed thereon, a second shaft having an opposing set of different-diameter gear-wheels 5 slidably mounted thereon, the first-named shaft being slidable longitudinally in its bearings, a cam, shifting rods connecting each movable gear-wheel independently with said cam, a rock-lever through which the movable shaft passes, being connected with said cam for rotating the same, and a lever pivoted to 10 said rock-lever and attached to said slidable shaft, whereby the movable members may be actuated through the manipulation of a single member, substantially as described.

19. In a variable-speed device, a shaft having a series of different-diameter gear-wheels fixed thereon, a second shaft having an opposing set of different-diameter gear-wheels 15

slidably mounted thereon, the first-named shaft being slidable longitudinally in its bearings, a cam, shifting rods connecting each movable gear-wheel independently with said cam, a rock-lever through which the movable shaft passes, being connected with said cam for rotating the same, a clutch adapted to 20 be engaged and disengaged by said shifting shaft, and a lever pivoted to said rock-lever and attached to said slidable shaft, whereby the movable members may be actuated through the manipulation of a single member, substantially as described.

In testimony whereof I have hereunto set my hand.

FREDERICK C. MILLER.
